EDWARD T. ADAMS, OF MILWAUKEE, WISCONSIN, ASSIGNOR TO ALLIS-CHALMERS COMPANY, OF MILWAUKEE, WISCONSIN, A CORPORATION OF NEW JERSEY.

PISTON.

961,080.

Specification of Letters Patent. Patented June 7, 1910.

Application filed October 18, 1909. Serial No. 523,334.

To all whom it may concern:

Be it known that I, EDWARD T. ADAMS, a citizen of the United States, residing at Milwaukee, in the county of Milwaukee and 5 State of Wisconsin, have invented a certain new and useful Improvement in Pistons, of which the following is a specification.

This invention relates to improvements in the construction of pistons for steam or 10 other fluid pressure engines.

The object of the invention is to provide a piston which will be simple and durable in its construction and efficient in operation. In pistons of large diameters it is customary 15 to form the interior hollow and also to annularly build up the body of several independent pieces. It is to this type of piston that the invention has particular relation.

20 A clear conception of the invention can be obtained by reference to the accompanying drawings in which like reference characters designate the same or similar parts in different views.

25 Figure 1 is a central vertical section of a piston built according to the invention, showing also a fragment of the piston rod. Fig. 2 is a plan view of the device shown in Fig. 1, a portion thereof showing a section taken along the line I—I of Fig. 1. Fig. 3 is an 30 enlarged fragmentary central vertical section of the piston shown in Fig. 1. Fig. 4 is a fragmentary plan of the device shown in Fig. 3. Fig. 5 is a view similar to that of 35 Fig. 3 but on an enlarged scale, showing a modification applicable to a narrower type of piston. Fig. 6 is a plan of same.

The piston body 3, see Fig. 1, is fastened to the rod 1 by means of the nut 2 which clamps 40 the body 3 against a fixed collar 5 upon the rod 1. The dowel 4 which coacts in a slot in the body 3 and in a corresponding hole in the rod 1, prevents rotation of the body 3 relative to the rod 1.

45 The body 3 consists of two parallel concentric disks which are tied together by the radial ribs 6. The pockets formed between consecutive ribs 6 and the disks have openings 13 near the periphery of the body 3. 50 In the preferred form of construction, see Figs. 1, 2, 3, 4, the openings 13 are covered by a ring 9, the outside diameter of which corresponds to the outside diameter of the body 3, and the distance between the planes 55 of the faces of the ring which are in clamp-

ing contact with the piston is equal to the distance between the plane surfaces of the piston with which the ring coacts.

In the modification, see Figs. 5, 6, the ring 9 coacts against the second ring 20, 60 which in this case forms a covering for the openings 13. This ring 20 is of a thickness equal to the distance between the plane surfaces of the piston, with which surfaces the rings 9, 20 coact. One of the plane surfaces 65 of the second ring 20, which surfaces are in contact with either ring 9 or piston 3, may be cut away a slight amount so as to leave a remaining surface of contact lying entirely without the circle of bolts. A packing ring 70 8 is located between the ring 9 and the peripheral rib 7 forming a part of the body 3 in the preferred form, and between the ring 9 and the second ring 20 in the modification.

The long studs 10, one end of which is 75 screwed into the body 3, have their other ends flush with the outer face of the body 3 on the ring side thereof. The ring 9 has a series of circular pockets 14 formed therein concentric with the holes which allow the 80 passage of the studs 10 through the ring. The studs 10 do not coact with the rings 9, 20, the holes permitting their passage therethrough being of greater bore than the diameter of the studs 10. These pockets 14 85 are of a depth equal to the height of the nuts 11. Radial slots 12 are formed in the ring 9 and body 3, which are directed toward the centers of the pockets 14.

The ends of the studs 10 have two slots 90 16 formed therein, which intersect each other at right angles. Each of the outer faces of the nuts 11 has holes 17 emerging therefrom, which holes 17 pass through the nuts 11 so as to register with the slots 16 95 of the studs 10 when the nuts 11 are secured upon the studs 10. A pin 15 passes through two of the opposite holes 17 of the nut 11 and through one of the slots 16, 100 see Figs. 3, 4.

In constructing pistons of great thickness, the preferred form shown in Figs. 1, 2, 3, 4, is used, as the length of stud 10 required if the modifications were used, would be too great. The pockets having the 105 openings 13 are cored during the casting of the body 3, the openings 13 serving as a means for removing the cores. After the body 3, the rings 9 and the ring 8 have been machined, the studs 10 are screwed into the 110

body 3, the ring 8 is slipped into place and the ring 9 is brought up against the ring 8 and against the plane surfaces of the piston with which surfaces the ring coacts. The 5 nuts 11 are then screwed upon the ends of the studs 10 clamping the ring 9 tight against the body 3 on the plane surfaces of coaction of the two. The two members have their curved surfaces separated by a slight 10 air space. After the nuts 11 have been brought up against the ring 9, the pins 15 are dropped into the slots 12 which are in line with the holes 17 which register with slots 16. The pins 15 are then passed 15 through the holes 17 and slots 16 and bent over at the ends thus locking the nuts 11 into place. If it is desired to remove the nuts 11, the pins 15 are bent back and are withdrawn.

20 In the modified form, the construction is exactly the same except that the second ring 20 is inserted, this ring 20 being clamped between the ring 9 and the piston 3. This is done in order to permit the use 25 of as long a stud 10 as it is possible to use and still get the ring 8 in the desired position.

It will be seen that with the present construction the long studs 10 give the structure 30 a certain amount of elasticity so as to compensate for unequal expansion and contraction of the clamped parts and still retain them in clamped position. The studs themselves cannot expand up to the amount 35 of extension of the studs under tension so that the parts never become loose. The use of the lock nuts 11 gives an efficient arrangement for securing the various members together under any desired degree of tension.

40 Since the full diameter of the body 3 is the same as that of the ring 9, it will be seen that if for any reason the larger face 45 of the piston should be subjected to any extreme pressure, the studs 10 will not be subjected to any resulting abnormal pressure because none of this pressure is borne by the ring 9, all of it being taken by the larger face of the piston body 3. If the extreme pressure falls on the opposite face of 50 the piston, the studs 10 will be subjected to a compressive strain to approximately the extent of their cross section only. This is an important feature as such abnormal 55 pressures may easily ruin a piston in which

the clamping studs are subjected to abnormal tension at such times.

It should be understood that it is not desired to be limited to the exact details of construction shown and described, for obvious modifications will occur to a person skilled in the art. 60

It is claimed and desired to secure by Letters Patent:—

1. In a piston, a plurality of coacting members, means including a stud coacting with one of said members only, and a nut coacting with another of said members and with said stud, for holding said members in coaction, the elasticity of said studs being sufficient to 65 counteract shifting of the parts due to change in temperature.

2. In a piston, the combination of a piston body, a ring portion, and a stud coacting with said body only, and a nut coacting with 70 said stud and said ring portion for clamping said ring portion to said body, said stud being of comparatively great length between the points of application of said stud to said body, and said nut to said stud. 75

80 3. In a piston, a plurality of coacting members, means including a plurality of studs coacting with one of said members only, and a plurality of nuts coacting with said studs and with another of said members, for holding said members in coaction, the elasticity of said studs being sufficient to 85 counteract shifting of said members due to change in temperature.

4. In a piston, a piston body, a ring, a 90 stud fixed to said body and passing freely through said ring, and a nut on said stud for clamping said ring to said body, said stud being of comparatively great length between its point of attachment to said body and the 95 point of application of said nut to said stud.

5. In a piston, a body member, a ring member, and means including a long stud fixed to one of said members and passing freely through the other of said members, 100 and a nut coacting with said stud and with said other member, for clamping the members together.

In testimony whereof, I affix my signature in the presence of two witnesses.

EDWARD T. ADAMS.
